UNITED STATES PATENT OFFICE.

HEDLEY RUTLAND, OF YORK, PENNSYLVANIA.

ARTIFICIAL TOOTH.

1,073,365.

Specification of Letters Patent. Patented Sept. 16, 1913.

Application filed February 24, 1913. Serial No. 750,290.

To all whom it may concern:

Be it known that I, HEDLEY RUTLAND, a citizen of the United States, residing at York, in the county of York and State of Pennsylvania, have invented certain new and useful Improvements in Artificial Teeth, of which the following is a specification.

My invention relates to improvements in artificial teeth, and is designed especially to provide a novel means of attaching such a tooth to a base or dental plate or to bridge-work as is customary in dentistry.

The primary object of my invention is the provision of a simplified means of attachment of the artificial tooth to the plate or bridgework by means of which I secure a stronger adherence of the parts, insure a minimum of grinding, and distribute the pressure more equally over the attaching post or pin.

The invention consists essentially in the manner of attaching the tooth to the base and involves a slotted tooth adapted to in case an obliquely arranged post, the tooth being applied to the back and passed over the post at an angle, as will be more fully described hereinafter.

In the accompanying drawings I have illustrated one complete example of the physical embodiment of my invention constructed according to the best mode I have so far devised for the practical application of the principles of the invention, and it will of course be understood that, although I have illustrated only one tooth and its attaching means, a plurality of teeth may be independently applied in like manner.

Figure 1 is a front elevation of an artificial tooth involving the features of my invention. Fig. 2 is a vertical sectional view of a tooth attached to a plate according to my invention, and showing in dotted lines the position before initial movement of the tooth in attaching the same to the plate.

Fig. 3 is a view in perspective of a portion of the plate or bridgework with an attaching post integral therewith. Fig. 4 is a sectional view of the tooth. Fig. 5 is a top plan view of the tooth showing it attached to a plate. Fig. 6 is a back or rear view of the tooth. Fig. 7 is a top plan view of the tooth.

In the preferred embodiment of my invention I utilize the standard porcelain tooth designated as 1, which is made by

usual process and formed with a recessed socket 2. The side walls of the socket are recessed or countersunk to form grooves 3, 3, which, it will be apparent in the figures of drawing and particularly in Fig. 4, are obliquely arranged to incline outwardly from the top to the bottom of the socket 2. Thus the top of the grooves starts at the top and inner face of the tooth and extends obliquely the width of the socket, to the bottom of the same.

I have illustrated at 4 a portion of bridge work or back plate to which the tooth may be attached. The integral post 5 projects a considerable distance from the plate and is adapted to be incased by the slotted tooth. The plate is made of usual material and the integral post is fashioned with a pair of obliquely extended ribs 6, 6 which are projected in the same plane as the grooves 3 are to the perpendicular, and are therefore complementary thereto. The post is of course located at the front of the plate and is adapted to receive the tooth, or rather be incased by the tooth. The tooth may be held to the post by frictional contact therewith, or if desired a cement may be employed, as usual, to cause the parts to adhere.

In assembling the parts, the tooth is positioned so that the pair of grooves 3 may be made to slide over the ribs 6, see dotted lines Fig. 2. Starting in this position the tooth is pushed upwardly and the ribs guide the tooth inwardly, the parts being in frictional contact, the post with the socket as well as the ribs with the grooves. The continued movement of the tooth causes the tooth to be wedged in between the ribs and the plate 4, and as a rule this frictional engagement will be sufficient to hold the tooth in place. However, as a precautionary measure, if found desirable an adherent may be used as is customary to cement the parts together.

It will be apparent that continuous use of the tooth, after being located in proper place, will, through the upward pressure thereon, tend to force the tooth in closer frictional contact with the post and its ribs and the plate, thus compensating for any possible wear, and preventing the tooth from becoming loosened. It will also be apparent, that should the tooth be broken or marred in any manner, and it thus become desirable that a new tooth be substituted for the defective one, the removal of the defective

tooth may be easily accomplished, and a new tooth applied with facility. This performance is especially meritorious in that it permits the substitution of one tooth for another, without interference with the bridge-work or other permanent foundation.

From the above description taken in connection with the drawings it becomes evident that I have provided an artificial tooth and attaching means which accomplishes its purpose and performs its functions in an easy and efficient manner, and provides an economical and durable article of manufacture.

What I claim is:—

The combination with a dental plate, having an integral vertical post formed with an obliquely extending rib on each side thereof, of a complementary tooth recessed and grooved for the reception of said post and ribs, whereby the tooth may be wedged between the oblique ribs and the plate.

In testimony whereof I affix my signature in presence of two witnesses.

HEDLEY RUTLAND.
